ORNET

UNITED STATES PATENT OFFICE.

LARS R. JORGENSEN, OF SOUTH BERKELEY, CALIFORNIA.

DAM CONSTRUCTION.

1,282,087.

Specification of Letters Patent. Patented Oct. 22, 1918.

Application filed December 27, 1915. Serial No. 68,680.

To all whom it may concern:

Be it known that I, LARS R. JORGENSEN, a citizen of the United States, residing at South Berkeley, in the county of Alameda and State of California, have invented new and useful Improvements in Dam Construction, of which the following is a specification.

This invention relates to improvements in dams, and more particularly to masonry dams of the arch type.

It consists in the construction of multiple arches, each arch having the curvatures of the up-stream and down-stream portions, so designed that the lines of pressure coincide approximately with the axes of the arches. It also includes the strengthening of said arches by the use of reinforcing steel and the semi-stiffening of the buttresses.

It also comprises details of construction which will be more fully explained by reference to the accompanying drawings, in which—

Figure 1 is a plan view of a multiple arch dam.

Fig. 2 is a down-stream elevation of the dam.

Fig. 3 is a partial section of the arch, showing the method of reinforcing.

Fig. 4 is a section on line 4—4 of Fig. 5.

Fig. 5 is a section on line 5—5 of Fig. 4.

Fig. 6 is a partial down-stream elevation of the arch and buttress, showing the reinforcement.

Fig. 7 is a section on line 7—7 of Fig. 5.

Fig. 8 shows a plan view of the device designed to allow water to flow over the crest.

Fig. 9 is a section on line 9—9 of Fig. 8.

Fig. 10 is a down-stream elevation of the device described in Fig. 8.

In cases where the cañon sides are long, flat slopes toward the crest and much steeper toward the center, it will be most economical to construct one large arch A in the middle, placing the buttresses 2 for the arch at or near the points where the slope changes, and constructing arches of smaller spans on both sides to close the remainder of the gap. The length of the up-stream radius should, preferably, change in such a way that the inclosed angle is kept as constant as possible below the bottom of the buttresses; that is, below the line a, Fig. 2, on the large arch and below the line b on the smaller arches.

The portion of the arches above the lines

a and b, respectively, should be designed as ordinary arches, either with sloping faces or vertical faces; or in some places it may be economical to construct the large central arch with a substantial vertical face and the smaller arches with sloping faces. It may also be economical in places to make the lower portion of the arch vertical, or nearly vertical, even above the bottom of the buttresses, and the remaining top portion of the arch sloping, regardless of whether the length of the up-stream radius is changed or not, or whether all arches are of the same span or length.

Whenever the slope of the up-stream face of a multiple arch dam is comparatively steep and the spanning comparatively short, the difference of water pressure at the crown and at the abutments of the same arch section is not so very great. The relative difference is, of course, greatest at and near the crest. In such a case it will be economical and most practical to change the circular shape of the arch so that the center line of pressure coincides with the axis of the arch toward the crest only, where this deviation is the greatest (as shown in Fig. 1 of Patent #1,087,662, granted to me February 17, 1914) and then continue the arch as a circular arch at lower elevations where this deviation is small. In places where this deviation is only small, and not enough to warrant changing the shape of the arch, reinforcing steel should be placed on the side liable to tension, as shown at 4, in Fig. 3, along the haunches on the down-stream side.

It may also be advisable, in places where the whole arch is reinforced, to shift the reinforcement in such a way outside and inside the axis of the dam that the steel is placed on the side liable to tension during cold weather when the reservoir is empty, in the manner indicated at 4^a in Fig. 4; or it may be necessary to place both these kinds of reinforcements in the same structure, depending upon the stresses to be taken care of.

In order to strengthen the junction between the buttresses and arches in a multiple arch dam, reinforcing steel is placed in a vertical or sloping position, as the case may be, in such a way as to form a girder, as shown in Figs. 4 and 5. In Figs. 4 and 5 main rods 6 are shown with interconnecting tie rods. The number of these rods, however, is not material as any number

might serve as well. These rods are placed in such a manner as to give the buttresses sufficient strength to withstand an unbalanced arch push, such as would occur should 5 failure or part failure of any adjacent arch take place. The buttresses should also be stiffened with reinforcing steel 7, toward the down-stream edge, to take care of wind pressure and the tendency of large flat surfaces to collapse.

At 7, as shown in Figs. 4, 5 and 6, is an arrangement of steel rods to take up any possible tension, due to wind pressure or other causes. The vertical steel bars 7 are 15 tied together with horizontal or nearly horizontal steel rods in the usual manner.

In order to stiffen the flat vertical slab or buttress, reinforced concrete piers or counterforts are provided on each side. 20 These piers or counterforts 10 are provided with reinforcing steel rods 11 in the same manner as shown at 7, but in this case it is more effective, due to the greater depth of the resulting girder 12. Above the strut 25 elevation where there are no counterforts, reinforcing steel bars are placed in the buttresses, as shown at 9, Figs. 5 and 7 to take care of any cracking tendency that might develop in this part of the buttresses.

30 On high dams additional reinforced piers or counterforts are necessary toward the up-stream face, as the flat, comparatively thin buttresses become of large area. These counterforts may be given a slope toward 35 the up-stream face. The reinforcement in the main struts 13 and 13^a, shown between the buttresses, should be thoroughly tied to the reinforcement in the buttresses, as the main object of the struts is to stiffen the 40 whole structure. The main struts should be capable of withstanding both tension and compression, besides bending. To effect this they are provided with secondary cross struts 14 and reinforced knee-braces 15. At 45 times they may act as supports for a bridge across the individual arches.

Whenever a multiple arch dam is to be designed to allow water to flow over its crest safely, such a device, as shown at 16, 50 in Figs. 8, 9 and 10, will be of advantage. This consists of a trough attached to the down-stream face of the dam, following the curvature of this as closely as practical and provided with a horizontal slope toward 55 the exit end to facilitate the rapid flow of water. The exit end 16^a is to be at some distance outside of the down-stream edge of

the buttress so that the free flowing water body will reach the river entirely beyond the structure in a down-stream direction. A 60 pile of rock may also be placed to receive the falling water to waste its force on. The trough is to be made of reinforced concrete or metal, and, besides being attached to the down-stream face of the dam, is also supported on the struts between the buttresses. The crest of the dam should be shaped to facilitate overflow. In the middle of the trough is a raised division 17 which serves to divide and divert the body of water flowing over the crest.

Having thus described my invention, what I claim and desire to secure by Letters Patent is:—

1. A multiple arch dam having the junction of the arches and the corresponding buttresses provided with reinforcing rods embedded in each arch near the abutments and in the buttress near the up-stream edge, said rods being hooped or connected together to form a triangular structure in each buttress and connected with a system of reinforce struts located contiguous to the spring line of the arches. 75

2. In a multiple arch dam of the character described, a series of arches with spans decreasing outwardly from the deepest portion of the stream bed and the outermost arches sloping in an up-stream direction, buttresses uniting with the meeting ends of 80 the arches, a triangular reinforcement of rods extending into the arches and abutments, and a system of reinforced struts by which the rods and structure are united. 85

3. In a multiple arch dam of the character described, an arch reinforcement consisting of rods extending into the contiguous portions of the arches and the abutments, said rods being hooped or tied together, and a system of reinforced connecting struts with which the said hooped reinforcements are united. 95 100

4. In a multiple arch dam, a hooped reinforcing structure, in combination with one or more lines of continuous struts located 105 close to the springing lines of the arches and anchored at opposite sides of the cañon.

In testimony whereof I have hereunto set my hand in the presence of two subscribing witnesses.

LARS R. JORGENSEN.
